CLAIM

I claim the ornamental design for a bracelet, as shown and described.

DESCRIPTION

FIG. 1 is a front, side perspective view of a bracelet, showing my new design in an environment of use.

FIG. 2 is a front view of the bracelet of FIG. 1.

FIG. 3 is a left side view of the bracelet of FIG. 1.

FIG. 4 is a back view of the bracelet of FIG. 1.

FIG. 5 is a right side view of bracelet of FIG. 1.

FIG. 6 is a top view of the bracelet of FIG. 1; and,

FIG. 7 is a bottom view of the bracelet of FIG. 1.

The broken lines showing a human hand in FIG. 1 represent environmental subject matter only and form no part of the claimed design.
